UNITED STATES PATENT OFFICE

2,463,332

DRIVE MECHANISM

Edward F. Vanderbosch, Mishawaka, Ind.

Application July 19, 1945, Serial No. 605,915

2 Claims. (Cl. 74—141)

1

This invention relates to a drive mechanism, and particularly to a propulsion device for children's toy vehicles. It will be understood, however, that the device is adapted for other uses in which reciprocating or rocking motion is to be converted into rotary motion, such as for starters for outboard boat motors, etc.

The primary object of this invention is to provide a device of this character which is simple in construction, easy to assemble, smooth and positive in operation, small in size and compact.

A further object is to provide a device of this character wherein parts can be formed of sheet metal stampings to permit manufacture of the device at low cost.

A further object is to provide a device of this character actuated by a reversely moving member, in which the speed of rotation of a rotary driven member increases progressively as the actuating member moves in driving direction, so that the device has a high starting torque and an inherent smooth operating characteristic.

A further object is to provide a device of this character which is adapted to be actuated by torque acting in one direction and which has a simple spring arrangement for returning the parts in the opposite direction to starting position.

Other objects will be apparent from the description, drawing and appended claims.

In the drawing:

Fig. 1 is a side view of a toy scooter incorporating my improved propulsion device.

Fig. 2 is a fragmentary top plan view of the device.

Fig. 3 is an enlarged fragmentary longitudinal sectional view taken on line 3—3 of Fig. 4.

Fig. 4 is an enlarged fragmentary transverse sectional view taken on line 4—4 of Fig. 3.

Fig. 5 is a transverse sectional view taken on line 5—5 of Fig. 3.

Fig. 6 is a transverse sectional view taken on line 6—6 of Fig. 3.

Referring to the drawing, which illustrates one embodiment of the invention applied to a child's toy scooter, the numeral 10 designates a scooter having a horizontal frame 11 including a platform 12. A front post 13 is pivoted to frame 11. A handle 14 is mounted at the upper end of post 13 and a steering wheel 15 is journaled between forks at the lower end of the post. A rear wheel 16 is journaled at the rear end of the horizontal frame between rearwardly projecting fork arms 17.

A cup-shaped housing 18 is fixedly secured to

2

one of the fork arms 17, as best illustrated in Fig. 3. Housing 18 preferably has a reduced central off-set 19 at its outer end, a relatively larger concentric off-set 20 around which an opening 5 in arm 17 fits snugly for rigid connection by welding or the like with an annular wall portion 21 bearing against arm 17 in face engagement. A cylindrical wall portion 22 completes the housing 18. A bearing 23 fits in the central off-set 19 of the housing and journals one end of shaft 24 on which wheel 16 is fixedly secured. The other end of shaft 24 is suitably journaled in the other frame fork 17.

A sprocket 25 is splined on shaft 24 at 26 in spaced relation to bearing 23 and is positioned between the plane of housing wall portion 21 and the open end of said housing. A pair of discs 28 are journaled on shaft 24 on opposite sides of sprocket 5. Discs 28 are of larger diameter than the sprocket and are interconnected at spaced points and outwardly of the sprocket by pins 29. One pin 29 journals a pawl 30 having a detent or nose 31 engageable between the teeth of sprocket 25, and an oppositely projecting lug 32.

A sleeve 33 rotatably encircles shaft 24 adjacent to one of the discs 28. A pair of discs is mounted in spaced relation on said sleeve. The innermost disc 34 fits freely within the housing adjacent one of the discs 28 and has a flange 35 bent therefrom outwardly of the periphery of disc 28. Flange 35 has a central notch 36 therein which receives the end of lug 32 of pawl 30. The outer disc 37 fits freely within the open end of the cup-shaped housing with peripheral clearance. A plurality of pins 38 connect the two discs. A flat coil spring 39 is positioned between the discs 34 and 37, being anchored at 40 to one of the pins 38 and being anchored at 41 at an opening 42 in the housing portion 22.

At the inner portion of the device, one of the discs 28 has a collar 27 projecting therefrom toward bearing 23. A disc 43 is journaled on collar 27. Disc 43 has a cylindrical marginal flange 44 which is notched to fit around a radial plate 45 positioned outwardly of bearing 23 at the end of off-set 20 of housing 18. An abutment ring 46 is mounted on the end of collar 27, which collar may be flanged at 27' to retain said ring thereon. A spring plate or disc 47 is positioned between abutment ring 46 and the disc 43 to normally urge the latter against disc 28.

A fitting 48 is splined to a sleeve 33 outwardly of disc 37. Fitting 48 is provided with a cam shaped outer periphery, as best illustrated in

Fig. 4, which includes a radial shoulder at 49. The fitting is recessed adjacent said shoulder to receive therein one end of a chain 50 which is pivotally secured to the fitting at 51. The radial dimension of the off-set or shoulder 49 of the fitting is substantially equal to the thickness of chain 50. Consequently, when the chain is coiled around the periphery of the fitting more than one revolution, as illustrated in Fig. 4, the outer turns or coils will bear upon the inner coil, with the outer surfaces of the chain forming a continuation of the helix or progressive cam surface defined by the periphery of the fitting. The chain is selected for its property of coiling upon itself and maintaining alignment, for which purpose the type known as a cable chain is preferred.

The outer end of chain 50 is pivotally connected at 52 to a suitable actuating member. This member is here illustrated as a bell-crank lever pivoted at 53 at the rear end of platform 12 of the vehicle. One arm 54 of the lever extends rearwardly and upwardly from pivot 53 and normally bears upon coiled chain 50 as seen in Fig. 4. The other arm 55 is inclined forwardly and upwardly from the pivot 53 and mounts a pedal 56 positioned above platform 12 at its free end.

In the use of the vehicle illustrated, a child stands upon platform 12 and presses the pedal 56 downwardly and releases pressure therefrom, alternately. Depression of the pedal causes the lever arm 54 to swing upwardly and pulls upon the chain 50 to unwind or uncoil it and thereby rotate fitting 48 and sleeve 33 in counter-clockwise direction as viewed in Fig. 5, thus winding the coil spring 39. The rotation of the inner disc 34, being in a clockwise direction as viewed in Fig. 6, causes its notched flange 35 to tilt the pawl 30 to the position shown in Fig. 6 whereby the rotation of disc 34 is transmitted by pawl 30 through ratchet 25 to shaft 24.

Upon completion of the downward working stroke of pedal 56 and its release, the spring 39 uncoils to reversely rotate the discs 34 and 37 and the fitting 49, thereby re-coiling the chain 50. The reverse rotation of disc 34, counter-clockwise as viewed in Fig. 6, tilts the pawl 30 about pin 29 to a position wherein its nose or detent 31 is clear of the sprocket 27. In this connection, the spring pressure of disc 43 against the adjacent disc 28 introduces a drag effect which permits this pivoting of pawl 30. Discs 30 are otherwise free to rotate with disc 34, except upon subsequent initial actuating rotation of disc 34, when the repetition of the same drag action again permits pivoting of pawl 30.

It will be observed that the device is substantially noiseless because the pawl does not ride over the teeth of the sprocket in the normal position of the parts and because the manner in which the parts are mounted and the spring pressure of disc 43 against disc 28 avoids free play of the parts. At the same time, binding of the parts is avoided and free running journalized operation is achieved. This free running operation characterizes the device at all times and facilitates coasting. In other words, it is not necessary for the pedal to be in any particular position for coasting action to occur, so pumping of the pedal may be stopped at any time and the pedal held raised, depressed or at any intermediate position.

One of the primary advantages of the device resides in the smooth starting afforded by the coiled chain 50. It will be observed that at the start of the working stroke the angular move-

ment of the fitting 48 and associated rotatable parts is less for any given length of linear or longitudinal movement of the free end of chain 50 than at any other part of the working stroke, and that the ratio of angular rotation to linear movement of the chain increases progressively during the working stroke. Consequently, the device starts easily and has a soft pedal action or effect as distinguished from a device where the ratio between the movements of the driving and the driven members is constant. The advantage of this arrangement, particularly for starting or accelerating a toy vehicle, will be obvious.

Another advantage of the device is that it can be made of small size and the operating parts can be preassembled on a shaft and then inserted into the housing. It will be observed in this connection that only the bearing 23 and the plate 45 are fixed to the housing 18. All other parts, except the engagement of spring end 41 with the housing, are independent of the housing. The spring presents no great problem because it is located near the open end of the housing, and the opening 42 can extend to the edge of the housing to permit the spring to be slipped therein incident to endwise movement of the shaft to meet it in bearing 23.

The device is susceptible of various applications and uses, other than as a driving mechanism for vehicles. One such use is as a starting mechanism for internal combustion engines, such as for outboard motors for boats. Also various modifications of the device may be made within the spirit of the invention and the scope of the claims.

I claim:

1. In a drive mechanism, a housing, a shaft projecting into and journaled in said housing, a sprocket keyed to said shaft, a pivoted pawl engageable with said sprocket and having an outwardly projecting lug, a pawl carrier journaled on said shaft, a member engaging said pawl carrier and including a part interlocked with said housing, a spring pressing said member against said pawl carrier, a spring carrier journaled on said shaft and including a projection engaging said pawl lug, a coil spring anchored at opposite ends to said spring carrier and said housing, said housing receiving said sprocket, pawl, pawl carrier, spring carrier, pawl carrier engaging member, and both springs a fitting fixed on said spring carrier and positioned exteriorly of said housing, said fitting having a progressively cammed periphery, and a chain encircling said fitting, said chain being secured at one end to said fitting and having a free end adapted for connection with an actuator.

2. In a drive mechanism, a housing, a shaft journaled in said housing, a driving unit journaled on said shaft, a driven unit having a part keyed to said shaft adjacent said driving unit, shiftable connecting means supported by said shaft associated with said driven unit and controlled by rotation of said driving unit in one direction at higher angular velocity than said shaft for transmitting rotation from said driving unit to said driven unit, said driving unit normally holding said connecting means inoperative, a spring, a member pressed by said spring into frictional engagement with said connecting means, and releasably interengaging parts on said housing and said last named member respectively for locking said last named member against rotation with said shaft, a second spring carried by said driving unit, said driving and

driven units, connecting means, friction member and both springs being preassembled on said shaft and fitting within said housing, said second spring being detachably anchored to said housing, and an actuator carried by said driving unit and projecting from said housing.
